UNITED STATES PATENT OFFICE

JOSEPH W. GOSLING, OF SCHENECTADY, NEW YORK, ASSIGNOR TO GENERAL ELECTRIC COMPANY, A CORPORATION OF NEW YORK

DESIGN FOR A LIGHTING STANDARD

Application filed September 28, 1932. Serial No. 45,106. Term of patent 14 years.

To all whom it may concern:

Be it known that I, JOSEPH W. GOSLING, a citizen of the United States, residing at Schenectady, in the county of Schenectady, State of New York, have invented a new, original, and ornamental Design for a Lighting Standard, of which the following is a specification, reference being had to the accompanying drawing, forming a part thereof.

In the drawing, Fig. 1 is a diagrammatic view showing the complete outline of my new design for a lighting standard; Fig. 2 is an

enlarged view for the purpose of showing details of the upper part of the standard, the side and front views thereof being the same, and Fig. 3 is an enlarged view for the purpose of showing details of the lower part of the standard, the side and front views thereof also being the same.

What I claim is:

The ornamental design for a lighting standard, as shown and described.

In witness whereof, I have hereunto set my hand.

JOSEPH W. GOSLING.
